FLASHING

Joseph Blacher, Boston, Mass.

Application January 30, 1937, Serial No. 123,174

3 Claims. (Cl. 72—127)

The present invention relates generally to sheet metal flashings, and, more specifically, to that class of flashings known as through flashings, and it comprehends a construction designed to be effectively maintained in engagement with the material supporting it and with the material supported by it. More particularly, the present invention relates to sheet metal flashings composed of copper or galvanized iron or other rust resisting material, which are interposed horizontally between courses of masonry in building walls, being embedded in the cement or mortar joints between the said courses of masonry, such flashings being in lengths and in widths equal to, or in slight excess of, the lengths and the widths of the walls and being adapted to prevent downward seepage of water through the cement or mortar joints.

The present invention is embodied in a flashing having substantially parallel continuous drainage channels spaced apart at sensible distances, between each adjacent pair of which is disposed, substantially parallel to the continuous drainage channels, discontinuous inverted channels in series, the continuous drainage channels and the discontinuous inverted channels being preferably less wide at bottom than at mouth. Since the cross sections of such channels resemble trapezoids minus the longer parallel sides, such channels will hereinafter be termed channels trapezoidal in cross section.

The principal object of the present invention is to provide a flashing possessing regions designed to effect drainage in a preferential manner.

Another object of the present invention is to provide a flashing whose construction insures the maintenance of a drainage surface substantially plane along the direction transverse the continuous drainage channels.

Another object of the present invention is to provide a flashing having channels trapezoidal in cross section, since channels of such conformation in a flashing of the present character possess special merit.

Another object of the present invention is to provide a flashing of the character described which can be formed from sheet metal in an expeditious and economical manner.

The attainment of these and other objects by the present invention will become apparent when the following detailed description of the preferred form of the invention is read in conjunction with an examination of the accompanying drawing wherein like numerals of reference in-

dicate like parts in the several views, and wherein

Fig. 1 is a fragmentary view, in perspective, of a wall of a building, showing the flashing in situ between courses of masonry.

Fig. 2 is a transverse section of the flashing.

Fig. 3 is a longitudinal elevation of the flashing.

In the drawing, 1 designates the flashing having substantially parallel continuous drainage channels 2 and discontinuous inverted channels 3 in series, both types of channels being preferably trapezoidal in cross section and being separated by the flat portions 4 of the flashing. Between the discontinuous inverted channels 3 lie the flat portions 5 of the flashing: the flat portions 3 and the flat portions 5 of the flashing lie in a common plane surface. The flashing may be provided with edge portions which may be bent downwardly, as at 7, or upwardly, as at 8, the said edge portions being designed to control and direct the discharge of water accumulating upon the upper surface of the flashing.

The insertion of the flashing in a building wall is effected in the following manner: a layer of cement or mortar is spread upon a course of masonry, the flashing is laid thereon with the continuous drainage channels concave upward and oriented in the direction of intended drainage, the flashing is then pressed into the cement or mortar to an extent sufficient to cause the continuous drainage channels to become embedded therein, to cause an appreciable flow of the cement or mortar up into the discontinuous inverted channels, and to impart to the flashing any desired inclination to promote drainage, a layer of cement or mortar is then spread upon the upper surface of the flashing, filling the continuous drainage channels, and finally, courses of masonry are built up on the flashing, the weight of the courses of masonry serving to establish more intimate contact of the surfaces of the flashing with the cement or mortar.

When properly inserted in a building wall, the flashing exhibits the following characteristics: warping of the drainage surface of the flashing along the direction of drainage is impossible, due to the stiffening effect imparted to the flashing by the continuous drainage channels and, to a lesser extent, by the discontinuous inverted channels; movement of the flashing in a direction transverse to the direction of drainage is impossible due to the restraint of movement imposed upon the flashing by the coaction of the ridges of cement or mortar filling the continuous drainage channels and partially or completely filling

the discontinuous inverted channels, and movement of the flashing in a direction parallel to the direction of drainage is impossible due to the restraint of movement imposed upon the flashing 5 by the coaction of the convex surfaces of the discontinuous inverted channels and the superimposed layer of cement or mortar.

Since the cement or mortar is forced up into the discontinuous inverted channels by pressure exerted upon the flashing, the discontinuous inverted channels are not infrequently but imperfectly filled, due to the entrapment of air in the positioning of the flashing upon and in the layer of cement or mortar. Moreover, in the setting of the cement or mortar, there may occur a slight shrinkage thereof, so that the discontinuous inverted channels are then filled to a degree slightly less than are the continuous drainage channels. It has been found that channels trap- 10 ezoidal in cross section, and, in a less satisfactory manner and to a lesser degree, channels semicircular in cross section, will accommodate the slight changes in the areas of flashings, caused by the thermal expansion and contraction thereof, and the strains developed between the flashings and the cement or mortar, by changes in temperature, due to differences in the coefficients of expansion of the flashings and the cement or mortar, especially if the discontinuous inverted channels are not wholly filled 15 with cement or mortar.

The flashing herein described may be readily formed out of metal sheets by the use of suitably fashioned rolls, and thus, such flashing may 20 be produced expeditiously and in an economical manner, without the use of expensive equipment, in the average metal working shop.

What is claimed is:

1. A flashing comprising a flat continuous strip 40 of sheet metal embodying therein a plurality of parallel continuous flat-bottomed drainage channels, uniform in cross section throughout their lengths and spaced apart at sensible distances, and a plurality of discontinuous inverted flat-

bottomed channels, uniform in cross section throughout substantially their lengths, arranged in series interposed between and parallel to adjacent pairs of the parallel continuous drainage channels, the flat bottoms of the continuous 5 drainage channels and of the discontinuous inverted channels being disposed, respectively, below and above the flat continuous strip of sheet metal in planes parallel thereto.

2. A flashing comprising a flat continuous strip 10 of sheet metal embodying therein a plurality of parallel continuous flat-bottomed drainage channels, uniform in cross section throughout their lengths and spaced apart at sensible distances, and a plurality of discontinuous inverted flat- 15 bottomed channels, uniform in cross section throughout substantially their lengths, arranged in series interposed between and parallel to adjacent pairs of the parallel continuous drainage channels, the flat bottoms of the continuous 20 drainage channels and of the discontinuous inverted channels being of lesser widths than the mouths of their respective channels and being disposed, respectively, below and above the flat 25 continuous strip of sheet metal in planes parallel thereto.

3. A flashing comprising a flat continuous strip of sheet metal embodying therein a plurality of parallel continuous flat-bottomed drainage channels, uniform in cross section throughout their 30 lengths and spaced apart at sensible distances, and a plurality of discontinuous inverted flat-bottomed channels, uniform in cross section throughout substantially their lengths, arranged in series interposed between and parallel to adjacent pairs of the parallel continuous drainage channels, at distances markedly greater than the widths of the parallel continuous drainage channels, the flat bottoms of the continuous drainage channels and of the discontinuous inverted channels being disposed, respectively, below and above the flat 35 continuous strip of sheet metal in planes parallel thereto.

JOSEPH BLACHER.
